TIRE

Martin J. Di Salvo, Arcade, N.Y.

Application September 9, 1957, Serial No. 47,667

Term of patent 7 years

(Cl. D90—20)

Figure 1 is a perspective view of a tire showing my new design;

Figure 2 is a section through the tire taken on line 2—2 of Fig. 1.

The dominant features of my design reside in those portions shown in solid lines. The dotted line disclosure is understood as representing the repetition of the full line disclosure in Fig. 1.

I claim:

The ornamental design for a tire, as shown and described.
